VENETIAN SHADE

Gottfrid C. Lawson and Carl Lindquist,
Cleveland, Ohio

Application November 19, 1934, Serial No. 753,586

15 Claims. (Cl. 156—17)

This invention relates to shutter type, or what are known in the trade as "Venetian" shades for application to windows, porches and the like, and the principal objects of the invention include:

5 The provision of a shade of the type specified embodying improved features of adjustability and control;

A shutter type shade which is attractive and neat in appearance and design and which at the same time is capable of low-cost production;

10 A shutter type shade wherein the shutters and coacting parts are relatively light in weight yet possess ample strength and at the same time are economical to manufacture;

15 A shade of the class specified having an improved pull-cord control.

The foregoing and other objects and advantages will become apparent in view of the following description taken in conjunction with the drawings, wherein:

20 Figure 1 is a view in elevation of a window shade embodying the features of the invention in its preferred form;

25 Figure 2 is a fragmentary sectional plan view of part of the shutter operating mechanism, and Figure 3 is a view in side elevation of Figure 2 with certain parts included which are omitted from the latter figure;

30 Figure 4 is a fragmentary view in elevation and enlarged to show the structure more clearly than in Figure 1, certain parts being omitted;

Figure 5 is an enlarged view in end elevation of Figure 4 with certain parts in section;

35 Figure 6 is a view taken substantially on the line 6—6, Figure 4;

Figures 7, 8 and 9 are enlarged detail views of the grip or clutch mechanism for the pull cord;

40 Figures 10 and 11 are enlarged detail views in plan of the shutters for the shade; Figures 12 and 13 are sectional views taken substantially on the lines 12—12 and 13—13, Figures 10 and 11; and Figure 12a is an enlargement of one of the edge portions of Figure 12.

45 Referring in detail to the drawings, the side and top frame members of a window are indicated at 5 and 5a in Figure 1. A housing member 6 is suitably attached to the top frame member 5a and has secured thereto brackets 8 and 9. The housing 6 may be formed of sheet metal or the like and is shown of box shape in cross section.

50 The shade proper comprises a series of shutters or slats 10, and 11 and 11a. The shutters 11 and 11a which are the top and bottom shutters and

support the remaining shutters, are preferably of the form shown in Figures 11 and 13, while the shutters 10 constitute the body of the shade and are preferably constructed as shown in Figures 11 and 12.

5 The shutters 10 are preferably formed of pressed board, paper, or analogous material which at their side edges are provided with beads 10a, which preferably consist of sheet-metal strips bent over and clamped on said edges. The preferred method of securing the beads on the edges of the shutters is clearly shown in Figure 12a. The strips as here shown are each bent so that the edge faces lie at an angle to one another with the inner edges biting into the shutter on opposite sides thereof. The bead thus assumes an oblong tubular shape. The outer wall of the tube or bead is somewhat flattened so that there is set up a reinforcing action. We have found that this tubular bead formation gives more strength to a given girth or width and thickness of metal than can be obtained by the use of U-shaped or parallel-sided bead.

10 The top and bottom shutters 11 and 11a may be made of material similar to that used in the shutters 10 and are preferably formed with rolled or rounded edges 11b, which are free of the metal beads or edges 10a, note particularly Fig. 13. These rounded or rolled edges materially strengthen the supporting shutters and permit the use of light material in their construction.

15 The top and bottom shutters are formed with holes 12 and the intermediate shutters 10 with slots 12a through which the pull cord 7 passes. Connecting with each slot 12a is cord-removing slot or break 12b, note right-hand side of Fig. 10, which extends to and through the edge of the shutter. By slightly twisting the shutter, the break or slot 12b can be widened sufficiently to permit removal of the shutter from its cord, so

20 that any one or all of the shutters 10 may be removed without disassembling the entire shade or removing the cord.

25 At the left hand side of Fig. 10, a slot 12c is formed which serves the same function as the slot 12b, the difference being that in this instance the slot is of such width that the pull cord will pass through with some pressure but without requiring twisting of the shutter. This type of slot is better adapted to shutters made of material that may be damaged by twisting.

30 The intermediate shutters 10 and bottom shutter 11a are suspended from the top shutter 11 by straps 13, which may be made of canvas or analogous material, these straps being secured to

the top shutter preferably as shown in Figure 6, the upper ends of the straps 13 being inserted through slots formed in the edges 11b of the shutter 11 and detachably held in place by means of spring metal clips 14. This same construction is preferably adopted with respect to the lower shutter 11a, while the intermediate shutters preferably rest on cross straps 15, note particularly Figure 4. It sometimes happens that these straps stretch after a shade is hung, so that the shutters are thrown out of alignment. With the clip fastening just described, it is only necessary to bend the clips sufficiently to allow the strap to slip or the clip to be removed and the strap 15 can be adjusted as desired or readily removed for cleaning or repair.

It will be seen that when the top shutter 11 is rotated, this movement is transmitted to the bottom shutter 11a as well as the intermediate 20 shutters 10.

The shutter control mechanism is mounted on and housed by the bracket 9 and the box shaped housing 6. First referring to the means for raising and lowering the shutters, this is accomplished through the medium of pull cord 1 which is passed between grip or clutch members, to be described, carried by the bracket 9 and over pulleys 16, 16a and 16b, rotatably mounted in the housing 6, the cord extending downwardly 30 through the holes 12 and slots 12a and being knotted on the ends thereof to hold it in place with respect to the lower shutter 11a. It will be seen from Figures 2 and 4 that the cord has one end thereof extended over the pulleys 16 and 35 16a and down through the registering holes and slots in one extremity of the shutters, while the other end of the cord is extended and passed over the pulley 16b and downwardly through registering holes and slots in the opposite extremity 40 of the shutters, the looped end of the cord being provided with a slip buckle 17.

To provide accurate and convenient control for the dropped position of the shutters, clutch members 18 and 18a are provided and are rotatably 45 mounted on bearing pins 19 in the outwardly projecting legs 9a of the bracket 9. These clutch members are shown more or less in detail in Figures 7, 8 and 9 and are each preferably in the form of peripherally grooved segments spaced a predetermined distance apart with approximately 50 the lower half of each segment having a roughened or grooved gripping surface 18b. Both lengths of the pull cord 1 extend downwardly through these clutch segments. The weight of 55 the shutters 10 and 11 cause the latter to drop by gravity when the clutch segments release the cord 1. To cause the clutch segments to grip the cord, it is only necessary to swing the latter to one side or the other, whereupon the faces 60 of the clutch segments frictionally engage the cord and are rotated into gripping position. To release the cord, it is only necessary to pull downwardly until the segments are rotated to non-gripping position with the roughened surface free 65 of the cord, whereupon the latter may be released and the shutters drop to the desired adjusted position. Stops 18c limit the downward travel of the clutch segments.

It is desirable that both lengths of the pull 70 cord 1 be gripped by the clutch equally and in a positive manner so that one length of cord may not slip and cause misalignment and disarrangement of the shutters. To insure a positive and equal gripping action, regardless of whether or 75 not the cord lengths are of equal diameter or

bulk in cross section, each clutch segment has its gripping face formed so that it will exert a wedging action on the pull cord and crowd both lengths thereof between the segments, note particularly Figure 8, said face being provided with wedge-shaped sides 18d connected by substantially plane or straight intermediate portions which are normally held spaced from the cord. The clutch segments have, in effect, a five-point pressure or crowding action on the pull cord 10 lengths, as diagrammatically indicated by the arrows in Figure 8. Should the cord lengths slip regardless of this arrangement, the grooves 18b guide them toward the center of the clutch faces, since said grooves are formed or lie at an angle 15 pointing toward said center, or are herringbone shaped. By this means unequal slipping is further guarded against. This construction is of particular advantage in view of the frequent difference in cross-sectional bulk or diameter of 20 the cord lengths.

The control mechanism for tilting the shutters is also carried by the bracket 9 and comprises a shaft 19, which is mounted in bearings 20 forming part of the bracket 9, note particularly 25 Figures 2 and 5. The shaft 19 has secured on one end thereof a pulley 21 over which a pull or adjusting cord 22 is trained and is retained on the pulley by means of side brackets 23, which are secured to the housing 6 by means of screws 23a. 30 The shaft 19 is also provided with a worm 24 which meshes with a worm gear 25, note particularly Figure 4, the gear 25 being secured on a pin or shaft 26 which at one end is journaled in a depending portion of the bracket 9 and at 35 its opposite end is journaled in a bracket 27 secured to the upper shutter 11, note particularly Figure 2.

To adjust the tilted position of the shutters, it is only necessary to pull on the cord 22, thereby 40 rotating the pulley 21 which in turn rotates the gear 25 and shaft 26 through the worm 24.

It is desirable that the cord which is trained over the pulley 21 slip as little as possible so that the ends thereof will always be in substantial 45 alignment. Accordingly, the pulley 21 is formed with a plurality of holes 21a in the side walls which bound the grooved face of the pulley, which holes need not necessarily open out through the sides of said walls. These holes serve to 50 guide the cord into the pulley and to press the cord into the groove thereof with the proper tension. The surface of pull cords used for this purpose and especially those of the braided type is generally of somewhat roughened form and 55 the body of the cord more or less soft, so that the cord presses into the holes and sets up a frictional engagement therewith. To further insure against slipping of the cord on the pulley, resilient guides 21b and 21c are provided and are 60 mounted so that either one or both normally bears against the cord and presses the latter into the grooved face of the pulley. The tension of these members 21b and 21c may be regulated as desired.

From the foregoing, it will be seen that we have provided a shutter type window shade which may be easily and quickly adjusted and wherein the control or pull cords are located on one side of the shade convenient to one hand and which 70 do not require attachment to a nail or the like each time the shade is adjusted. If desired, one pull cord may serve both for raising and lowering as well as for tilting the shutters, in which event the looped end of cord 1 would simply be 75

continued around pulley 21 and the cord 22 eliminated. From actual experience, I have found that the shutters do not stick during the adjusting operation, and that adjustment may 5 be easily and quickly carried out. By making the shutters as specified, the cost of manufacture may be kept to a relatively low figure.

It will be understood that certain minor changes in structure may be adopted within the 10 scope of the invention as defined by the appended claims.

We claim:

1. In combination with a pull cord for a shutter of the class described, a clutch member therefor 15 comprising a pair of one-way gripping members having grooved surfaces defining a trackway for said cord, a portion of said surfaces being roughened so that the said members will be rotated into gripping engagement with said cord through 20 frictional contact therewith.

2. In combination with a pull cord for a shutter of the class described, a clutch member therefor comprising a pair of one-way gripping members having co-acting rotary members with working 25 faces arranged to provide a passageway through which the cord length extends, said faces each having transversely opposed side walls which are of converging, substantially wedge shaped contour to effect a crowding action on said pull cords 30 and insure an equal gripping action thereon.

3. In combination with a pull cord for a shutter of the class described, a clutch member therefor comprising a pair of co-acting oppositely disposed rotatable members having arcuate peripheries with grooved working faces adapted for frictional engagement with said cord, said faces having opposed side walls thereof converging toward one another in a substantially wedge shaped form adapted to exert pressure on the 40 outer opposed sides of the cord lengths to crowd said lengths together into the clutch groove to insure equal gripping of said lengths.

4. In combination with a pull cord for a shutter of the class described, a clutch therefor comprising 45 a pair of grooved arcuate faced segments rotatable in spaced relation to each other with the cord lengths trained therebetween, the grooved faces of the segments each having opposed side walls of substantially wedge shaped 50 formation adapted to exert a crowding action on the cord lengths, and a plurality of traction grooves formed in the lower half of each segment, said traction grooves being arranged at converging angles to guide the cord length toward the 55 center of the segment faces.

5. In combination with a pull cord for a shutter of the class described, a clutch therefor comprising 60 a pair of grooved arcuate faced segments rotatably mounted in spaced relation to each other with said cord lengths trained therebetween, a plurality of track grooves formed in the lower half of each segment arranged in herringbone shape to guide the cord lengths toward the center of the segment faces in event of slippage.

6. In combination with a pull cord for a shutter of the class described, a clutch therefor including 65 a grooved arcuate faced segment rotatably mounted to engage the cord, a plurality of track grooves formed in the lower half of said segment 70 arranged in herringbone shape to guide the cord lengths toward the center of the segment face in event of slippage.

7. In a Venetian blind, a rail from which the 75 blind slats are supported, a pulley mounted in said rail and from one side of which both blind

control cords depend, said rail having a bottom opening through which the cords extend, a dog connected to the rail beyond said side of the pulley on an axis parallel to the pulley and adapted to swing downwardly of its own weight, stop means limiting the downward movement of the dog, and a curved gripping face on the dog disposed eccentric to the axis thereof and with its eccentricity increasing from the top down. 5

8. In a Venetian blind, a rail from which the 10 blind slats are supported, a pulley mounted in said rail on an axis inclined to the horizontal and from one side of which blind control cords depend, said rail having a bottom opening through which the cords extend, a dog connected to the 15 rail beyond said side of the pulley on an axis parallel to the pulley and adapted to swing downwardly of its own weight, stop means limiting the downward movement of the dog, and a curved gripping face on the dog disposed eccentric to the axis thereof and with its eccentricity increasing from the top down. 20

9. In a Venetian blind, a top rail, a bracket secured to the top rail and having extensions extending into the top rail, a pulley supported by 25 said extensions, a dog pivotally supported by said bracket to one side of said pulley and having a gripping face eccentric to its pivot.

10. In a Venetian blind, a top rail, a bracket secured to the top rail and having parallel side 30 walls provided with extensions extending into the top rail, a pulley supported by the extensions within the top rail, a dog pivotally supported between the side walls of the bracket at one side and below said pulley, and having a gripping face 35 eccentric to its pivot.

11. In a Venetian blind, a top rail, a bracket secured at an angle to the top rail and having parallel side walls provided with extensions extending into the top rail, a pulley supported by 40 the extensions within the top rail at an angle inclined to the horizontal, a dog pivotally supported between the side walls of the bracket at one side and below said pulley, and having a gripping face 45 eccentric to its pivot, said pivot for said dog being parallel to the axis of the pulley.

12. In a Venetian blind having slats adapted to be raised, lowered, and/or tilted by control cords, a top rail and a raising, lowering and tilting mechanism, a bracket therefor, said bracket including a pair of parallel side walls secured to the top rail at an angle and extending into the top rail, said angularity being such that the control cords may be operated spaced from the 55 window.

13. In a Venetian blind having slats adapted to be raised, lowered, and/or tilted by control cords, and mechanism for raising, lowering and tilting the same, a top rail, a bracket for supporting said mechanism including a bracket body secured to the top rail at an angle and adapted to support said mechanism at such an angle that the control cords for operating the mechanism may be operated spaced from the window. 60 65

14. In a Venetian blind having control cords for raising and lowering and control cords for tilting the same, a top rail, a control bracket having parallel side walls, portions of which extend into said rail, a pulley rotatably supported 70 in the rail on said bracket, a clutch supported below the rail between the walls of said bracket, the parallel walls of said bracket being inclined with respect to the rail so that the control cords which extend through the clutch and over said 75

- 5 pulley may be operated spaced from the window, a tilt mechanism supported at the lower end of said bracket including a shaft rotatably journaled in the bracket and having an operating sheave adapted to receive a cord thereover for frictionally rotating the same, the axis of said shaft being inclined to the horizontal to permit said cord to be operated at a point spaced from the window.
- 10 15. In a Venetian blind, a top rail, a control bracket having parallel side walls and formed with extensions protruding into the rail above the bottom, the parallel walls of said bracket being

inclined with respect to the rail, a pulley rotatably supported in the rail on said bracket, and a clutch supported below the rail between the walls of said bracket, a tilt mechanism supported at the lower end of said bracket including a shaft rotatably journaled in the bracket, the axis of said shaft being inclined to the horizontal, an operating sheave disposed on an end of the shaft adapted to receive a cord thereover for frictionally rotating the same. 5
